UNITED STATES PATENT OFFICE

DONNA E. MINTON AND SENETH H. GALLAGHER, OF PARSONS, KANSAS

CONCRETE BURIAL VAULT

Application filed September 13, 1928. Serial No. 305,736.

The present invention relates to concrete burial vaults and has for its principal object to provide a moisture absorbing compartment or chamber within the vault adapted to 5 retain a quantity of moisture absorbing material whereby to absorb any moisture which may enter the vault through the walls thereof and thus to maintain the interior of the vault in a dry condition.

10 A further object of the invention is to provide a tray adapted for fitting within the vault at the upper portion thereof whereby to form the moisture absorbing compartment and arranged to be sealed within the vault 15 together with the top of the vault.

A still further object is to provide an article of this character of a neat and attractive appearance, which is strong and durable, relatively inexpensive to manufacture 20 and otherwise well adapted for the purposes for which the same is intended.

Other objects and advantages reside in the special construction, combination and arrangement of the various elements forming 25 the invention as more fully hereinafter described and claimed, reference being had to the accompanying drawings forming part hereof, wherein like numerals refer to like parts throughout, and in which:

30 Figure 1 is a perspective view of the vault with the top shown in position thereon,

Figure 2 is a longitudinal vertical sectional view therethrough,

Figure 3 is a transverse vertical sectional 35 view therethrough, and

Figure 4 is a top plan view of the tray for the moisture absorbent material.

Referring now to the drawing in detail, for the purpose of illustration, we have illustrated 40 a burial vault of substantially rectangular formation as indicated generally at 5 and preferably constructed of reinforced concrete or similar plastic composition.

The vault is open at its upper portion and 45 is provided on the inner face of each of its walls, adjacent the upper edge thereof, with a downwardly beveled shoulder 6. Within the upper portion of the vault is fitted a tray 7, likewise constructed of reinforced concrete 50 or the like, said tray opening upwardly and

disposed with its upper edges substantially at a horizontal plane with the upper edges of the walls of the vault 5.

The lower edges of the tray are also beveled as illustrated in Figures 2 and 3 of the drawing whereby to provide a snug fit with the beveled surface of the shoulders 6. The base of the tray is formed with a plurality of openings 8 extending therethrough whereby to provide communication between the interior of the vault at the lower portion thereof and the space above the bottom of the tray.

The tray is filled with a quantity of absorbent material indicated at 9 of any suitable character well known in the art possessing 65 moisture absorbing qualities. The inner walls of the vault, between the shoulder 6 and the upper edge thereof, and the outer surface of the walls of the tray 7 are formed with horizontally extending grooves 10 and 11 respectively formed at a horizontal plane with respect to each other and combining to form a channel within which mortar 12 may be poured between the cracks between the walls of the vault and the sides of the tray, 75 said channel, when filled with the mortar constituting an interlocking retaining means for the tray within the vault as well as serving to seal the air space about the edges of the tray.

The top 13 of the vault is then placed upon the upper edges of the walls of the vault and the tray and is likewise secured in position by the mortar. The top 13 is also constructed of reinforced concrete or other plastic composition.

It will be apparent from the foregoing that after the tray and top have been fitted in position within the walls that moisture is prevented from entering the same and any 90 moisture contained in the bottom portion of the vault will readily be absorbed by the absorbent material 9 placed in the tray.

The interior of the vault will thus be maintained in a dry condition.

It is obvious that our invention is susceptible to various changes and modifications in construction without departing from the spirit of the invention or the scope of the appended claims, and we accordingly claim 100

all such forms of the device to which we are entitled.

Having thus described our invention, what we claim as new is:

1. A burial vault open at its top side and having a reduced position on the inner walls adjacent the upper edges thereof forming a downwardly bevelled shoulder, a tray arranged within the vault and having bevelled lower edges seating upon said shoulder with its upper edges flush with the top edges of the vault, said tray having openings formed in the bottom thereof to provide communication between the interior of the tray and the interior of the vault, and a quantity of absorbent material arranged within the tray; and a cover seated upon the top edges of the walls of the vault and of the tray, having its outer edges flush with the outer surfaces of the walls of the vault, and a plastic binder poured between the walls of the vault and the walls of the tray and upon the top edges of the walls of the vault and of the tray for securing and sealing the tray and the cover in the said positions with respect to the vault.

2. A burial vault of the type described comprising a burial vault having an open top and having a reduced portion about the upper inner surface of its walls defining a downwardly bevelled shoulder, and a tray having the lower edges of its walls bevelled to register with said shoulder and rest thereupon when the tray is in position within the vault, the upper edges of the walls of the tray being flush with the upper edges of the walls of the vault when in said position, and a plurality of apertures in the bottom portion of the tray providing communication between the interior of the tray and the interior of the vault, and a quantity of absorbent material within the tray, and a cover for the vault comprising a plate adapted to rest upon the upper edges of the walls of the vault and of the tray and to have its outer edges flush with the outer surfaces of the walls of the vault and a plastic binder flowed between the walls of the tray and of the vault and upon the upper edges of the tray and vault for sealing the joints therebetween and securing the tray and cover in position with respect to the vault.

In testimony whereof we affix our signatures.

DONNA E. MINTON.
SENEATH H. GALLAGHER.
